Inventor:

Richard L. Barrett.

Richard L. Barrett
Atty.

UNITED STATES PATENT OFFICE.

RICHARD L. BARRETT, OF CHICAGO, ILLINOIS.

GREASE CUP.

Application filed January 12, 1920. Serial No. 351,015.

To all whom it may concern:

Be it known that I, RICHARD L. BARRETT, a citizen of the United States, residing at Chicago, in the county of Cook and State of Illinois, have invented certain new and useful Improvements in Grease Cups, of which the following is a specification.

Heretofore considerable difficulty has been experienced with grease cups of this character, and particularly where they have been located in some inconvenient or not readily accessible position, in that when the cap has been removed to fill the cup with grease, it is difficult to properly position the cap back upon the cup so that the screw threads will register, and when the cap is forced upon the cup, the threads will be mutilated or stripped.

Furthermore it frequently happens that the cap will work its way off of the cup and become lost.

To overcome these difficulties and objections and to provide an improved device of this character embodying a cap having a plunger therein provided with screw threads adapted to engage the threads of the cup, and having means whereby the plunger will be properly positioned and guided when the cap is applied, so that the threads will register and engage, is one of the objects of the present invention.

A further object is to provide improved means for detachably securing the cap in position.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which:

Figure 1 is a side elevation.

Figure 2 is a side elevation with the parts in a different position from that shown in Figure 1.

Figure 3 is a vertical longitudinal sectional view with parts in elevation.

Figure 4 is a view similar to Figure 3 with the parts in a different position.

Referring more particularly to the drawing, the numeral 10 designates a grease cup of any desired size and external configuration, having a threaded stem or portion 11

by means of which the cup may be secured to a suitable part 12 by means of an angular portion 13 on the stem and which angular portion is adapted to receive a wrench or tool, all as usual in grease cups of this character.

The cup is provided with internal screw threads 14 and is also provided with an outlet opening 15 through which the grease is forced from the cup.

A cap 16 is also provided, the internal diameter of a portion of which is slightly greater than the external diameter of the cup 10 so that the cup 10 may be passed into the cap 16. This cap 16 is provided with an end 17 which is closed except for an opening 18 located centrally thereof and surrounding the opening is a collar 19 forming an extended guide for a plunger 20 and which is adapted to pass therethrough. One end of 75 the plunger 20 is enlarged as at 21 and this enlarged portion is of a diameter slightly less than the interior diameter of the cup 10. The enlarged portion 21 is provided with peripheral screw threads 22 which are 80 adapted to engage the threads 14 on the interior of the cup 10 so that when the plunger 20 is rotated by means of a suitable handle 23, the threads 22 on the portion 21 of the plunger will engage the threads 14 85 of the cup and will cause the plunger to be advanced or retracted according to the direction of rotation of the plunger. The cap 16 extends for any desired distance above the top of the cup 10 and has provided there- 90 in a recess 24 into which the enlarged portion 21 of the plunger is adapted to enter so that the threads on the portion 21 may be entirely disengaged from the threads 14 95 in the cup to permit the cap 16 and plunger 20 to be removed as a unit from the cup when desired.

The cap 16 may be detachably secured to the cup in any suitable manner, but preferably by means of a bayonet slot construction 100 embodying one or more bayonet slots 25 arranged preferably in the lower edge of the cap, and one or more pins 26 carried by the outer wall of the cup 10 so that when the cap is placed in position the pins 26 will enter 105 the bayonet slots 25 and after the cap is rotated with respect to the cup, the parts will be locked together. If desired a suitable spring 27 may be provided which extends over the bayonet slots and is provided with 110

recesses 28 to receive the pins 26 and assist in securing the parts against accidental displacement.

If desired the walls of the slots 25 may be 5 inclined so that the pins 26 will be wedged therein.

It is thought that the operation of this improved device will be readily understood from the foregoing, but briefly stated it is 10 as follows. The threads 22 on the enlarged portion 21 of the plunger 20 are first detached from the threads 14 of the cup which will cause the enlarged portion 21 of the plunger to be seated in the recesses 24 of 15 the cap. The cap is then rotated with respect to the cup to position the pins 26 in alignment with the inlet openings of the bayonet slots. The cap may then be lifted from the cup. The cap can then be re-applied by 20 first positioning the bayonet slots to receive the pins 26 and then rotating the cap to lock the parts together.

When the parts are in this position it will be seen that the collar 19 around the opening 25 18 forms an extended guide or bearing for the plunger 20 so as to always correctly position the enlarged portion 21 of the plunger, so that the screw threads thereon will accurately register with the threads 14 in the cup, 30 thereby insuring the proper starting and guiding of the plunger into the cup no matter what amount of grease is contained within in the cup.

With this improved construction it will be 35 manifest that the threads on the co-operating parts will be preserved and when the parts are locked together it will be impossible for them to become accidentally separated or detached.

40 If desired and in order to assist in securing the parts together the cap 16 may be provided with a knurled or serrated portion 29.

Obviously the plunger 20 and the handle 23 thereon can be constructed in any suitable 45 manner so as to permit the parts to be readily assembled.

While the preferred form of the invention has been herein shown and described, it is to be understood that various changes may 50 be made in the details of construction and in the combination and arrangement of the several parts, within the scope of the claims without departing from the spirit of this invention.

What is claimed as new is:—

1. A grease cup embodying a cup proper having internal screw threads and provided with a smooth exterior surface, a cap for the cup, a skirt connected with the cap and adapted to be freely slipped over the cup and to engage the periphery of the cup, a plunger operable in the cup and having peripheral threads adapted to engage the threads within the cup, there being an opening in the cap, a bearing encompassing the opening, said plunger being freely slidable in the bearing, and means whereby the plunger may be rotated with respect to the cap the said skirt serving to insure an initial positioning of the plunger exterior of the cap proper that the threads on the plunger will be properly positioned to engage the threads in the cup. 60 65 70

2. A grease cup embodying a cup proper having internal screw threads and provided with a smooth exterior surface, a cap for the cup, a skirt connected with the cap and adapted to be freely slipped over the cup and to engage the periphery of the cup, a plunger operable in the cup and having peripheral threads adapted to engage the threads within the cup, there being an opening in the cap, a bearing encompassing the opening, said plunger being freely slidable in the bearing, means whereby the plunger may be rotated with respect to the cap, the said skirt serving to insure an initial positioning of the plunger exterior of the cup proper that the threads on the plunger will be properly positioned to engage the threads in the cup, and means detachably securing the cap to the cup. 75 80 85 90

3. A grease cup embodying a cup proper, a cap therefor and into which cap the cup telescopes means detachably securing the cap and cup together a plunger operable in the cup, there being an opening in the cap through which a portion of the plunger extends, and a handle secured to the plunger for operating the same from the outside of the cap, said handle embodying a piece of sheet material bent upon itself to form spaced arms, and between which arms the end of the plunger is secured. 95 100

In testimony whereof I have signed my name to this specification, on this 30th day of December, A. D. 1919.

RICHARD L. BARRETT.
